FREDERICK L. HUMESTON, OF NEW HAVEN, CONNECTICUT, ASSIGNOR, BY MESNE ASSIGNMENTS, TO WINCHESTER REPEATING ARMS COMPANY, A CORPORATION OF DELAWARE

BATTERY HAND LAMP

Application filed May 21, 1927. Serial No. 193,149.

This invention relates to battery hand lamps of the type including a casing for the battery, a lamp bulb surrounded by a suitable reflector, a switch mechanism for completing the electric circuit through the bulb, a bottom end cap, and a lens or end glass for the bulb and reflector. The present invention particularly relates to the provision of an improved construction of hand lamp incorporating means for varying or focusing the beam of light projected by the lamp by varying the position of the lamp bulb relative to the reflector.

In hand lamp focusing means of the general character described, it has heretofore been the practice to maintain the battery in direct contact with the lamp socket, and to move the battery with the lamp socket and the lamp bulb relative to the reflector and the lamp casing in varying the character of the beam of light. The present invention has for its principal object the provision of improved adjustable supporting means for the lamp socket, together with improved means for supporting and effecting electrical connections with the battery, these means being combined in such a manner that the battery remains stationary with respect to the casing while the lamp socket is moved to obtain the desired focus of the light beam.

Further objects of the invention are to group the several elements compactly so that a casing of minimum length can be used, to provide for economical manufacture and assembly of the several parts, to provide for ready access to the various parts of the hand lamp mechanism, in case repairs are necessary, and to insure against short circuiting of the battery and inadvertent lighting of the lamp.

Other specific objects, advantages and characteristic features of the invention will become apparent as the description thereof progresses.

In describing the invention in detail, reference will be made to the accompanying drawings, in which:

Figure 1 is a sectional side view of a hand lamp embodying the focusing means of the present invention;

Fig. 2 is a sectional view taken along the line 2—2 of Fig. 1, and viewed in the direction of the arrows; and

Fig. 3 is a sectional view taken along the line 3—3 of Fig. 1, and viewed in the direction of the arrows.

Referring to the drawings, the hand lamp comprises, in general, a cylindrical casing C, preferably formed of sheet metal, a bottom end cap B having a screw threaded or other suitable connection with the lower end of the casing, and a flared head H suitably secured to the upper end of the casing C as by the rivets 1 and carrying a retaining ring 2, an end glass or lens 3, and a reflector 4. The reflector 4 is of substantially parabolic section, and is gripped at its outer edge between the lens 3 and an annular support formed by the upper inturned edge 5 of the head H. The lens 3 may be plane as shown, or may be curved in any suitable manner. A reinforcing ring 6 is provided between the annular support 5 and the retaining ring 2. This reinforcing ring may be in the form of a piece of wire bent to form a loop, and inserted in a suitable annular recess 7 formed in the retaining ring 2. This reinforcing ring, when arranged in the manner described, is permanently associated with the retaining ring 2 so that when the retaining ring is unscrewed, the reinforcing ring remains in position in its annular groove or seat. The reflector 4 is firmly held against the support 5 by the retaining ring 2, which clamps lens 3 against the rim of the reflector 4 and forces this rim into firm contact with the annular support 5. The ring 6 forms a substantial support or reinforcing means for the outer end 5 of the head H.

The hand lamp is provided with the usual battery 8, preferably composed of a plurality of dry cells arranged end to end in series connection and enclosed in a suitable insulating container 9. An electric connection between the lower end of the battery 8 and the casing C is effected by means of a coiled spring 10 which is preferably retained within the bottom end cap B by the expansion of the largest coil thereof in an internal groove 11 in the cap.

The upper central terminal 12 of the battery 8 contacts with a metallic rivet 13 secured in the center of a disc shaped partition 14 of insulating material which is fixed with respect to the casing C. The pressure exerted by the spring 10 on the lower end of the battery 8 maintains the terminal 12 in firm and continuous contact with the rivet 13. A U-shaped contact strip 19 of resilient sheet metal is secured to the partition 14 on its upper side by the rivet 13, and forms an electrical connection between the terminal 12 of the battery 8 and the lamp socket, as herein-after described.

The partition 14 is circular in form, having a substantially rectangular opening or notch 15 at the edge thereof as shown in Fig. 3. An inwardly projecting circular ledge or extension 16 is provided in the wall of the casing C at a point just above the inner end of the battery 8, and the partition 14 is firmly clamped between this ledge and a resilient supporting ring 17 which is expanded into a circular groove 18 in the casing wall as shown in Figs. 1 and 3. It will be readily apparent that the means just described comprise an efficient support for the partition 14, and the construction of these means enables the partition to be quickly and easily assembled in the casing without the aid of special tools or complicated fastening devices. The ledge 16 and the groove 18 are preferably formed integral with the casing wall as shown, and are easily pressed or turned from the sheet metal of which the casing is formed.

Any suitable type of switch means may be employed in connection with the hand lamp of the present invention for controlling the flow of current through the lamp bulb. In the embodiment shown, a switch housing 20 is suitably secured to the casing wall, and encloses a switch mechanism comprising a thumb actuated push button 21 at one end of a resilient conducting strip 22 which is readily secured in electrical connection with the housing 20 by means of a rivet 23. A stationary conducting strip 24 is secured within the casing wall by rivets 25 and is insulated from the casing by the insulating strips 26 as shown in Figs. 1 and 3. The conducting strip 24 extends upward through the notch or opening 15 in the partition 14, and has an outwardly inclined lower end 27 extending into the switch housing 20 through an opening 28 in the wall of the casing C. When the button 21 is depressed into contact with the end 27 of the strip 24, an electric circuit is completed from the lower end of the battery 8, through the spring 10, the end cap 11, the casing C, the strip 22 and button 21 to the strip 24. A sliding thumb piece 29 carries a finger 30 which, by the inward pressure of the push button 21, is disengaged by a slot in the strip 22, permitting the thumb piece 29 to be pushed forward to hold the switch in closed

condition for lighting the lamp continuously.

An incandescent lamp bulb 31 is threaded into a metal socket 32 which is electrically connected with the stationary conducting strip 24 by means of a radially extending conductor 33 which is in direct contact with the lamp socket. A metallic rivet 34 passes through the bottom of the lamp socket 32 and serves to form an electrical connection between the central terminal of the lamp and the resilient conducting strip 19.

The lamp socket 32 is carried by a three-legged support or spider 35, the three legs of which project through three slots 36 in the casing C in such a manner that the support 35 can be moved longitudinally of the casing. The head H of the hand lamp is provided with screw threads 37 at the inner end thereof, and a threaded ring 38 having an annular groove 39 therein is adapted to be screwed on to this threaded portion 37 of the head H. The projecting legs of the lamp socket support extend through the slots 36 into the annular groove 39 within the ring 38, so that when this ring is turned the support 35 is caused to move axially with respect to the casing C in one direction or the other, depending upon the direction of rotation of the ring 38 with respect to the casing C. The outer ends of the legs of the support 35 are disposed nearer to the battery than the portions which engage the adjusting ring 38.

An insulating washer 41 is provided in the base of the metal lamp socket 32 for the purpose of insulating the socket from the central rivet 34. The conductor 33 encircles the rivet 34, but is insulated therefrom by a small insulating washer 42. The support 35 is provided with a central opening into which is fitted a piece of insulating material 43. The insulation 43 is in the form of a washer encircling the rivet 34, and is preferably fixed relative to the support 35 in such a manner that rotation between these parts cannot take place. An insulating washer 44 is provided for the purpose of insulating the conductor 33 from the support 35. A metallic washer 45 is provided under the lower head of the rivet 34, and this washer and the rivet are insulated from the support 35 by a washer 46 of insulating material. A sleeve 50 of insulating material is preferably provided over the lamp socket 32 as shown, being retained in position by frictional engagement with the socket. This sleeve serves to prevent electrical contact between the reflector 4 and the lamp socket 32 when the retaining ring 2 together with the reflector 4 is removed from the head H.

Means are preferably provided to prevent the lamp socket and the conductor 33 from turning or rotating with respect to the washer 43 and the support 35. As pointed out above, the washer 43 is rigidly secured to the support 35 by any suitable means, and a lug 47 is

struck from the base of the lamp socket 32, this lug extending downwardly through a notch 48 in the conductor 33 and into a depression 49 in the washer 43. In this manner, both the lamp socket 32 and the conductor 33 are permanently locked to the washer 43 and as this washer is rigidly fixed to the support 35, it is impossible for the socket or the conductor to turn from the proper position when the lamp bulb 31 is screwed into the socket, even though the central rivet is loose.

From the description given, it will be seen that the hand lamp of the present invention includes many advantageous features. The lamp socket is so supported that the position of the lamp bulb may be readily adjusted with respect to the reflector, thus varying the character of the light beam projected by the lamp. Although the lamp socket and bulb are readily adjustable, the battery is retained stationary at all times, and the electric connections to the battery and between the cells thereof are therefore permanently maintained. The partition 14 serves to divide the lamp casing into a battery compartment and a lamp compartment, the battery being held stationary on one side of this partition, whereas the lamp and its socket are adjustably mounted on the other side of the partition. The various parts of the hand lamp are so constructed and arranged that they can be easily and cheaply manufactured and readily assembled.

Although the present invention has been described in connection with a single specific construction of hand lamp, it is to be understood that the invention is equally applicable to hand lamps of various types other than that disclosed. Various changes in the details of construction can be made and various parts can be modified or omitted without departing from the scope of the invention as defined by the appended claims.

I claim:

1. In a hand lamp, a casing, a battery within said casing, a reflector fixed in one end of said casing and having an opening therein, a lamp socket, means for adjustably supporting said socket in the opening of said reflector to move relative to said reflector, an inwardly extending ledge on the wall of said casing between said battery and said socket, a partition resting on said ledge, conducting means extending through said partition for electrical connection with said battery, and an expandable spring member fixed to said conducting means and electrically connecting said lamp socket to said conducting means.

2. In a hand lamp, a casing, a lamp bulb adjustably mounted in said casing, a battery in said casing, a ledge on the inner wall of said casing between said bulb and said battery, an insulating partition resting on said ledge, a groove in the casing wall parallel to said ledge and spaced therefrom a distance

substantially equal to the thickness of said partition, a resilient split ring in said groove for clamping said partition in engagement with said ledge, conducting means extending through said partition and engaging the central terminal of said battery, and a resilient conducting spring fixed to said partition by said conducting means and engaging said lamp socket, said spring and said conducting means electrically connecting said lamp socket to said battery terminal regardless of adjustable movement of said lamp socket.

3. In a hand lamp, a tubular casing, a reflector having an opening therein fixed in one end of said casing, a lamp socket adjustably supported adjacent to opening in said reflector, a partition in said casing adjacent said lamp socket, spaced inwardly extending means for fixing said partition against movement relative to said casing, a battery in said casing on the opposite side of said partition from said lamp socket, conducting means passing through said partition and engaging a terminal of said battery, and a resilient conducting member secured to said partition in engagement with said conducting means and with said lamp socket for completing an electrical connection between said battery terminal and said socket.

4. In a hand lamp, a tubular casing, a lamp bulb adjustably mounted in one end of said casing, a partition for dividing said casing into a battery compartment and a lamp compartment, and means for supporting said partition in said casing comprising a circular ledge on the inner wall of said casing for engagement with one side of said partition, a circular groove in said wall parallel to said ledge and spaced therefrom, a resilient split ring expanded into said groove and engaging the other side of said partition, conducting means extending through said partition and engaging a terminal of said battery, and a spring in said lamp compartment fixed to said conducting means and electrically connecting said lamp bulb to said conducting means.

5. In a hand lamp, a casing, a battery and reflector coaxially arranged and retained in fixed positions with respect to each other, a lamp support within the casing, a socket carried by said lamp support, means encircling and threaded to the front of said casing for moving said lamp support with respect to said reflector and battery to change the spread of the beam of light delivered by said lamp, a connecting member extending through said support into the bottom of said socket, said member being insulated from said support and said socket, and a resilient connection between said connecting member and the positive pole of said battery.

In testimony whereof I affix my signature.
FREDERICK L. HUMESTON.
